UNITED STATES PATENT OFFICE.

WILLIAM H. LUDEWIG, OF ROCK ISLAND, ILLINOIS.

SURGICAL OPERATING-ENGINE.

No. 812,507.

Specification of Letters Patent.

Patented Feb. 13, 1906.

Application filed December 30, 1904. Serial No. 238,947.

To all whom it may concern:

Be it known that I, WILLIAM H. LUDEWIG, of Rock Island, in the county of Rock Island and State of Illinois, have invented new and useful Improvements in Surgical Operating-Engines; and I hereby declare that the following is a full, clear, and exact description thereof, reference being had to the accompanying drawings, which form part of this specification.

This invention is an improvement in surgical instruments, and is an operating-engine especially designed to be held in the hand and used as the operative handle for saws, files, chisels, and other instruments used by physicians in operations in nasal passages and other internal cavities of the body. The engine is also adapted for use with dental instruments, such as pluggers and cutters.

The invention is particularly designed for operating reciprocating instruments, such as saws; but I do not restrict myself to such use except when so specified in the claims. Moreover, the engine may be used by artisans in the mechanic arts if properly proportioned, and while, as stated, it is particularly designed for use by surgeons and dentists I do not limit myself to such use.

The several novel features of the engine and combinations of parts therein for which protection is desired are summarized in the claims and will be clearly understood from the following description, in connection with the accompanying drawings, which illustrate the best form of the invention now known to me, but are not intended to be restrictive thereof.

In said drawings, Figure 1 is a side view of the complete engine with a saw attached. Fig. 2 is a top view of Fig. 1. Fig. 3 is a horizontal section. Fig. 4 is a section on line 4, Fig. 1. Fig. 5 is a section on line 5, Fig. 1. Fig. 6 is a top plan view of the part B. Figs. 7 and 8 are detail views of the rods E F detached. Fig. 9 is a horizontal sectional view showing a slight modification, in which the balancing-rod is omitted. Fig. 10 is a similar view of another modification, in which a rotary tool-holder is employed. Fig. 11 is a detail side view of another modification.

The preferred form of engine shown in Figs. 1 to 8 comprises two hollow parts A and B, one end of the latter being slidably fitted into the open end of the former, so as to

be supported thereby, but projecting therefrom. The part A is provided with a depending handle A' of such size and form as will enable the operator to grasp it firmly and comfortably. From one side of part A projects a tubular stud a, in which is journaled a shaft C, on the outer end of which is fixed a driving-gear c, which is preferably a frictional gear. The inner end of shaft C is provided with a double crank c' c'' for a purpose herein-after explained. The gear c may be protected by a housing a', attached to the outer end of stud a, as shown. The part B is also provided with a laterally-projecting stud b, in which is journaled a shaft D, on which is a gear d, adapted to contact or mesh with and drive gear c when moved toward it. The stud b projects through a slot A² in the side of part A, as shown in the drawings, so that studs a b are parallel. The gear d is protected by a housing b', screwed on the outer end of stud b, as shown. The gears c d may be of any suitable peripheral contour, and I now prefer to have one ridged and the other grooved, as indicated in Figs. 9 and 10, but of course do not restrict myself to any specific form of gear.

The outer end of shaft D may be threaded, as at D', and the housing b' may have a threaded extension b'', so that the engine may be connected to the terminal of a sheathed flexible shaft, (not shown,) such as are commonly employed in dental and surgical offices and which can be operated by an electrical or other suitable motor. (Not shown.) Shaft D, however, may be driven in any desired manner, the particular power connection of the motor therewith being immaterial.

Part B is provided with a depending finger-piece B', resembling a trigger, which can be grasped by the finger of the operator's hand and forms part of the handle of the engine, and by drawing trigger B' toward handle A' gear d is brought into contact with gear c and the latter is driven. Normally the gears are separated by means of a suitably-arranged spring. As shown in Figs. 1 and 2, a bent spring I is interposed between the studs a b and tends to push them apart and normally holds part B in its projected position. The outward movement of part B is limited by a screw b⁴, tapped thereinto through a slot a⁴ in the lower wall of part A.

Part B is hollow, and therein are placed two

reciprocating rods E and F, the inner ends of which are widened and flattened, as at E' F', and project into slots e' f' in part B. Said ends E' F' are vertically slotted, as at f' e', and 5 are respectively transfixed and engaged by the cranks c' c² on shaft C, so that by rotating the said shaft the rods are reciprocated. The outer ends E² F² of rods E F are preferably rounded and pass through openings in the ends 10 of part B, as shown. As the rods E F are operated by diametrically-opposed cranks, they counterbalance each other and prevent or materially lessen vibration of the engine. The 15 projecting ends of the rods E F may be formed for the attachment of tools. As shown, only the rod E has its end threaded, and a tool-holder head G is attached thereto, said head being slotted, as at g, for the insertion of the shank of a tool or instrument and is provided 20 with a thumb-screw g' to secure the instrument thereto.

As shown in Fig. 9, the rod F is omitted, only the rod E being used, and this is centered in part B, and the shaft C is provided with 25 but a single crank c³, engaging the slot in head E'. The gear c is shown with convex V edge adapted to engage a concave V edge in gear d; otherwise the construction and operation is substantially the same as of the tool shown in 30 Fig. 1.

In Fig. 10 instead of a reciprocating rod a rotary rod J has one end journaled in part A, and the other end projects through and is journaled in part B and has a tool-holder on 35 its outer end, to which a rotary tool, such as a bur, can be attached. On the shaft J is a bevel-gear j, which is adapted to mesh with a like gear c on the inner end of shaft C, by which 40 rotary motion is imparted from shaft C to shaft J. The journal of the shaft J in part B is such as will permit part B to move sufficiently to bring gear d into mesh with gear c. By this construction rotary movement of the 45 tool is obtained.

In Fig. 11 part A is made long enough to contain the operative parts, and part B instead of supporting the operative parts is made into a box-slide B⁴, fitted on part A, but carries the shaft D, gear d, and finger-piece B', 50 so that the operation of the parts is controllable by the grip of the operator, as in the other constructions. In Fig. 11, moreover, is shown a modified arrangement of separating-spring. Instead of the spring I an expansive helical 55 spring M is strung on a rod m between the handle A' and finger-piece B' and normally tends to move the part B⁴ and separate the gears c d.

Operation: The instrument or tool to be 60 used is attached to the head G, and shaft D is connected to any suitable motor. The operator then positions the tool, using the engine merely as a handle, and when positioned he grips the handle A' more firmly and with his

forefinger moves part B inward, so as to bring 65 gear d into mesh or contact with gear c, whereupon motion is imparted to the shaft C and the latter reciprocates the bars E F with great rapidity. The bar F is preferably made heavier than bar E, so that it will counterbalance 70 the weight of the bar E and attached tool, and thus reduce the vibration of the engine to the minimum. By simply relaxing the grasp of the forefinger the engine is stopped.

The utility of this engine-handle is self-evident, and its adaptability to surgical and dental purposes is apparent. It is also obvious that if made of sufficient size and weight the engine is adapted for general use in the arts, and the preferred form is particularly useful 80 where reciprocating or vibratory tools are employed.

Having thus described my invention, what I claim as new, and desire to secure by Letters Patent, is—

1. In an engine of the character specified, the combination of a pair of relatively movable members, a crank on one member, a reciprocating rod on the other member adapted to be actuated by said crank, and means for 90 rotating said crank.

2. In combination, a pair of relatively movable members, a double crank on one member, a pair of reciprocating rods on the other member adapted to be actuated in opposite directions by said crank; and means for rotating said crank, substantially as and 95 for the purpose set forth.

3. In combination, a member provided with a handle, a movable member, a crank on the first member, a reciprocating rod on the movable member actuated by the crank, and means on the movable member adapted to operate the crank, substantially as set forth.

4. In combination, a member provided 105 with a handle, a second member slidably supported on the first member, a double crank on the first member, a pair of reciprocating rods on the movable member, respectively actuated by one of the cranks and means on 110 the movable member adapted to operate the crank-shaft when moved toward the latter, substantially as set forth.

5. In combination, a relatively stationary 115 part, a relatively movable part, a crank-shaft journaled on the stationary part, a driving-shaft journaled on the movable part, means for transmitting motion from the driving to the crank shaft when the former is moved toward the latter, and a reciprocating rod attached to the movable member and operated by the crank-shaft, substantially as described.

6. In combination, a relatively stationary part provided with a handle, a relatively movable part connected with the stationary part and supported thereby, a crank-shaft journaled on the stationary part, a driving-shaft journaled on the movable part, and gearing

for transmitting motion from the driving to the crank shaft when the former is moved toward the latter; with a reciprocating rod attached to the movable member and adapted to be operated by the crank-shaft, and a tool-connecting device on the rod, substantially as described.

7. In combination, a member provided with a handle, a crank-shaft journaled in said member, and a gear on said shaft; a movable member projecting from the stationary member, a driving-shaft journaled on said movable member; opposed gears on said shafts, adapted to be brought into coöperative relation by moving the movable member toward the handle, means for normally separating the gears, a reciprocating rod mounted on the movable member and operated by the crank-shaft, and means for connecting an instrument to said rod, substantially as described.

8. In combination, a hollow stationary member provided with a handle, a shaft journaled in said member having a crank on its inner end, and a gear on its outer end; a hollow movable member supported in and projecting from the stationary member, a driving-shaft journaled in said movable member, and a gear on said shaft adapted to contact with the gear on the crank-shaft when the movable member is drawn inward, a spring for normally separating the gears, and a reciprocating bar mounted in said movable member and engaging the crank on the crank-shaft, and means for connecting an instrument to said rod, all substantially as and for the purpose described.

9. In combination, a stationary member provided with a handle and a tubular stud, a crank-shaft journaled in said stud, and a gear on said shaft; a movable member, a finger-piece on the movable member for drawing it toward the handle, a tubular stud on said movable member, a driving-shaft journaled therein; opposed gears on said shafts, adapted to be brought into coöperative relation by moving the movable member toward the handle, means for normally separating the gears, a pair of reciprocating rods mounted in the movable member and operated by cranks on the crank-shaft, and means for connecting an instrument to one of said rods, substantially as described.

10. In combination, a hollow stationary member provided with a handle, a tubular stud projecting from said member, a shaft journaled in said stud and having cranks on its inner end within the member, and a frictional gear on its outer end; a hollow movable member supported in and projecting from the stationary member, a finger-piece depending from said movable member, a laterally-projecting hollow stud on said member, a driving-shaft journaled in said stud, and a frictional gear on said shaft adapted to

contact with the gear on the crank-shaft 65 when the movable member is drawn inward, a spring for normally separating the gears, and a pair of reciprocating bars mounted in said movable member and engaging the opposite cranks on the crank-shaft, and means 70 for connecting an instrument to one of said rods, all substantially as and for the purpose described.

11. In an engine of the character specified, the combination of a tool-operating member, 75 a driven shaft, means for operating the said member from said shaft; and a support for said parts adapted to be held in the hand; with a driving-shaft also mounted on said support, gears for transmitting motion from 80 the driving-shaft to the driven shaft, means for holding said gears normally out of contact, and a finger-actuated device whereby the gears may be moved into operative contact, substantially as set forth.

12. In combination, a member provided with a handle, a rotatable shaft journaled on said member, a second member connected with said first member, a rotatable shaft on the second member, gears on said shafts 90 adapted to be brought into operative contact by relative bodily movement of the members, a tool-actuating rod or shaft, and means for operating said rod from the first-mentioned shaft, substantially as and for the 95 purpose described.

13. In combination, a member provided with a handle, a rotatable shaft journaled on said member, a second member slidably connected with said first member, a rotatable shaft on the second member, gears on said shafts adapted to be brought into operative contact by moving one member upon the other, a spring interposed between said members to keep the said gears apart, a tool-actuating rod mounted in said members, and for operating said rod from the first-mentioned shaft, substantially as and for the purpose described.

14. In combination, a member provided with a handle, a laterally-projecting shaft journaled on said member having a gear on its outer end; a second member movably mounted on the first member and having a laterally-projecting shaft, and a gear on said shaft, said gears being brought into operative relation by moving the members relatively, a spring for separating said gears, and a tool-actuating rod actuated by said first-mentioned shaft, substantially as and for the 120 purpose described.

15. In combination, a member provided with a handle, and a laterally-projecting sleeve, a shaft journaled in said sleeve having a gear on its outer end; a second member 125 slidably mounted upon the first member and having a depending finger-piece and a laterally-projecting sleeve, a shaft journaled in

4
said sleeve, and a gear on said shaft, said gears being brought into operative relation by moving the latter member upon the first member, a spring for separating said gears, 5 and a reciprocating tool-actuating rod actuated by said first-mentioned shaft, substantially as and for the purpose described.

In testimony that I claim the foregoing as my own I affix my signature in presence of two witnesses.

WILLIAM H. LUDEWIG.

In presence of—

FRANK X. BICKEL,

Wm. C. SCHOEMAKER.
